UNITED STATES PATENT OFFICE

2,460,118

CIRCUIT INTERRUPTER

Robert M. Bennett, Birmingham Township, Chester County, Pa., assignor to General Electric Company, a corporation of New York

Application July 21, 1945, Serial No. 606,374

3 Claims. (Cl. 200—147)

1

My invention relates to improvements in circuit interrupters and more particularly to improvements in arc extinguishing devices for circuit breakers for controlling circuits carrying alternating currents especially over a wide range in altitude as in certain aircraft installations.

The proposal to use on aircraft three-phase alternating current systems at the relatively high frequency of 400 cycles per second introduced many problems. Even though the voltage of the A.-C. systems is relatively low, 208 Y/120, it is several times greater than the voltage of the D.-C. systems which have been used in aircraft. With the paucity of information available on the interruption of alternating currents at altitudes from ground level to 50,000 feet or more, some of those skilled in the art of circuit interruption contend that only compression type arc interrupters can be used. Such devices, because of their weight and complexity, are not ideally suited for aircraft application. Tests indicate that the frequency is of little consequence in the matter of interruption. Wide range of altitude is the principal difficulty. At low altitudes, that is, relatively high atmospheric pressure, the cooling effect on the arc is comparatively large because of the high density of the air. This materially reduces the cross section of the arc because the more rapidly it is cooled, the smaller the cross section becomes. Also, because of the greater current density, the inherent loop expansion or self-blowout effect of the arc is more effective with decrease in cross section of the arc. At high altitude or low atmospheric pressure, the cross section of the arc is large, and since the current density is relatively small, the loop expansion effect is reduced. Consequently, the arc is sluggish and difficult to move. In order satisfactorily to dissipate a high current density arc of small cross section with an open arc chute, a certain measure of restriction of the arc is required so that it cannot escape from the chute before it is sufficiently cooled. On the other hand, the sluggish, low current density arc of large cross section, which is difficult to move, must not be unduly restricted or it will tend to hang before that restriction. It therefore becomes necessary to provide means which functions satisfactorily to extinguish arcs having

2

such diverse characteristics because of the altitude factor. Furthermore, such means must be relatively light in weight, relatively simple in structure and particularly reliable in operation for use on aircraft and especially aircraft for fighting purposes.

An object of my invention is to provide for circuit interrupters an improved open type arc extinguishing device which is effective in interrupting alternating currents over a wide range in altitude. Another object of my invention is to provide an improved arc extinguishing device which combines opposing arc chute plates open at their top, front and bottom edges with a 10 nesting U-shaped magnetic blowout member having wide upwardly offset perforate flange portions embracing the arc chute plates and a relatively narrow magnetic web partially closing the lower part of the gap between the rear edges 15 of the plates together with a magnetizing conductor looped around the web and interconnecting a stationary switch contact mounted between the plates in front of and adjacent the magnetic web and a terminal stud mounting head located 20 behind a barrier closing the upper part of the gap so as to provide a concentrated and effective magnetic arc extinguishing structure that is very compact and lightweight. A further object of my invention is to provide an improved 25 magnetic arc extinguishing device requiring a minimum of parts when combined with a specially-formed cooperating circuit breaker structure. These and other objects of my invention will appear in more detail hereinafter.

30 In accordance with my invention, I provide an open type arc chute wherein two spaced plates of electrically insulating material are shaped to provide a converging or diminishing arc discharging channel at the top. Also in accordance 35 with my invention, I provide a magnetic blowout structure comprising a U-shaped magnetic member having upwardly offset flanged portions embracing the outer faces of the chute plates and whose web portion is relatively narrow and partially closes the lower part of the gap between the chute plates at their rear edge. Further in accordance with my invention, the lead-in conductor to a stationary contact resiliently mounted between the chute plates adjacent the web portion 40 of the U-shaped member is looped around

this web portion. Still further in accordance with my invention, the U-shaped member is of uniform thickness with its upwardly offset sides perforated to reduce weight while at the same time distributing the magnetic blowout flux more widely over the converging or diminishing discharge channel in the upper part of the arc chute. Also in accordance with my invention, the upper part of the gap between the arc chute plates at the rear edges thereof is closed by an insulating barrier that shields the main terminal stud mounting head and the lead-in conductor therefrom to the stationary switch contact.

My invention will be better understood from the following description when considered in connection with the accompanying sheet of drawings, and its scope will be pointed out in the appended claims.

In the accompanying drawing, Fig. 1 is a side elevation, partly in section and partly broken away, of an arc extinguishing device embodying my invention; Fig. 2 is a side elevation of the embodiment of my invention shown in Fig. 1; Fig. 3 is a front end elevation of the embodiment of my invention shown in Fig. 1; and Fig. 4 is an exploded perspective of the embodiment of my invention shown in Fig. 1.

In the illustrated embodiment of my invention, I have shown an arc extinguishing device of the magnetic blowout type with an open arc chute comprising two spaced plates 1 and 2 of suitable electrically insulating material such, for example, as disclosed in United States Letters Patent 2,366,485, issued January 2, 1945 and assigned to the assignee of this invention. For magnetic blow-out purposes, I provide around two sides and the rear edge of the arc chute a U-shaped magnetic member which has, in the vertical direction, relatively wide upwardly offset flange portions 3 and 4 contiguous to the outer parallel faces of the plates 1 and 2, respectively, and a relatively narrow web portion 5 across the gap between the plates at the rear edge thereof. For best magnetic properties and minimum weight, the flanges and web of the U-shaped member are formed from one piece of suitable magnetic material of uniform thickness, and the flanges are perforated so as to provide substantially the same magnetic cross section as the web portion 5 as shown more clearly in Fig. 4.

Between the plates 1 and 2 and adjacent and in front of the web portion 5 of the U-shaped member, I mount a relatively stationary contact 6 of suitable material which meets the requirements of low operating temperature, high welding current, short arc duration and minimum contact deterioration. For meeting these requirements, I have found that a contact made of a sintered mixture of silver and tungsten is satisfactory.

Cooperating with the relatively stationary contact 6 is a contact 7 mounted for movement between the plates 1 and 2 near the lower edge thereof to engage the contact 6 and separable therefrom to interrupt a circuit within the chute formed by these plates. The arrangement by which the movable contact 7 is actuated to and from the closed circuit position is immaterial as far as my invention is concerned, but I have illustrated part of a circuit breaker mechanism which is the subject matter of copending application, Serial No. 582,053, filed March 10, 1945 by John A. Favre and assigned to the assignee

of this invention. Thus, as shown, the contact 7 is mounted on a rigid current conducting arm 8. This arm is supported on a pin 9 mounted in a channel shaped carrier 10 which is supported on a suitably insulated member 11 carried by a shaft 12 so as to turn upon movement of the shaft. To the arm 8 is connected a flexible lead 13 which extends to the lower terminal, not shown, of the circuit breaker.

In accordance with my invention, I so mount the relatively stationary contact 6 in front of the web portion 5 of the U-shaped member as to have an electric current conducting member such as a flexible lead 14 from a terminal stud 15 looped around the web portion and connected to the contact 6. Thus, as shown, contact 6 is resiliently supported on leaf spring means 16 which is suspended from or secured to the terminal stud 15 by suitable means such as a rivet 17 passing through holes in the spring means and through holes in a stud plate head 18 secured to the stud 15 and a spacer plate 19. While some current may pass through the leaf spring means 16, it is to be noted that only one leaf of the spring is attached to the contact 6. The resistance of this spring, because of its small cross section, is such that only a very small fraction of the current in the circuit breaker is by-passed around the conductor loop 14. The web portion 5 may be suitably insulated by a shield of insulating material 20 which comes down from between the stud plate 18 and the spacer plate 19 around the back of the web portion 5 between the conductor 14 and the web portion and around the front of the web portion between the leaf spring means 16 and the web portion.

In order to insure at low altitudes the desired arc cooling action before the arc passes out of the chute without preventing blowout of the arc at high altitudes, the plates 1 and 2 are shaped to provide a converging arc discharging channel, the cross section of which will be most clearly obvious from Fig. 3. For this purpose, approximately the lower half of each of the plates 1 and 2 is of uniform thickness and approximately the upper half of these plates increases substantially uniformly in thickness at their adjacent faces to provide a converging arc discharging channel. To prevent blowdown of the arc below the stationary contact 6, I provide an insulating shield positioned below the contact 6. This shield may conveniently consist of two parts 21 and 22, as shown more clearly in Fig. 4, which are respectively molded on or form a part of the plates 1 and 2. As will be apparent from the exploded perspective of Fig. 4, these projections 21 and 22 overlap, when assembled as in Figs. 2 and 3, to provide underneath the contact 6 a continuous shield extending from the back edge of the chute to in front of the contact 6.

For maintaining the assembly of the chute, I provide at the front a rivet 23 which passes through openings 24 in the flanges 3 and 4 of the U-shaped member and through openings 25 in the plates 1 and 2, these latter openings being recessed to receive a tubular spacer 26 of suitable insulating material through which the rivet 23 also passes. For maintaining the assembly at the rear of the chute, the flanges 3 and 4 of the U-shaped member are provided with extending ears 27 which are bridged by a cross member 28 of nonmagnetic material suitably secured to the ears 27. The stud plate 15

is positioned in front of this bridging piece 28 and separated therefrom by an insulating spacer 29.

For locking the parts in position at the rear of the chute and also shielding the leaf spring means 16, I provide a spacer member 30 of suitable insulating material which fits snugly between recessed portions 31 in the plates 1 and 2 and against the leaf spring means 16 and comes to rest with its projecting flanges 32 against the top edges of the plates 1 and 2. The shield 38 is provided with a recessed opening 33 for receiving the head of the rivet 17. The whole assembly is then secured to the insulating base 34 of the switch by securing the stud 15 to the base with a nut 35 and suitable washers 36. For securing the lower edge of the chute firmly to the base 34, the plates 1 and 2 may be provided with downwardly projecting portions 37 which are abutted by the head of a T-shaped member 38 of suitable insulating material which is suitably secured to the base 34 as by a screw 39. In order to secure a firm wedging action at the top of the rear edge of the chute, the stud plate 18 is tapered at its lower end to fit snugly against correspondingly tapered shoulders 40 on the plates 1 and 2.

With the foregoing described arrangement of elements, when the current flows through the flexible lead 14, the U-shaped member is magnetized in such a way that the flux tending to pass between the sides 3 and 4 of the U-shaped member is in a direction tending to push the arc upward in the chute by virtue of the joint magnetic action between the flux field around the arc and the transverse flux field between the flanges 3 and 4 of the U-shaped member. The arc is thus rapidly distended, but at low altitudes it is unable to escape from the converging arc discharging channel until it is sufficiently cooled to be rapidly extinguished in the vicinity of the throat of this channel. On the other hand, at high altitudes where the arc is sluggish, there is a strong magnetic action tending to keep the arc moving and the cross section of the arc is reduced by the magnetic action which drives the arc into the converging channel where it is cooled sufficiently to be interrupted.

Because of the relatively light weight of the parts, particularly the magnetic blowout structure and also the compactness of the arc quencher and the rigidity of the structure, circuit breakers embodying my invention are particularly adapted for use on aircraft over a wide range in altitude.

While I have shown and described my invention in considerable detail, I do not desire to be limited to the exact arrangement shown, but seek to cover in the appended claims all those modifications that fall within the true spirit and scope of my invention.

What I claim as new and desire to secure by Letters Patent of the United States, is:

1. In an electric switch, an arc chute open at the top, front and bottom edges thereof comprising two oppositely spaced rectangular plates of electrically insulating material having an insulating barrier therebetween for closing substantially the upper half of the gap between the plates at the rear edge thereof, approximately the lower half of said plates being of uniform thickness and approximately the upper half of said plates increasing substantially uniformly in thickness at their adjacent faces to provide a converging arc discharging channel at the top

thereof, a U-shaped magnetic member of uniform thickness having relatively wide upwardly offset perforated flange portions contiguous to the outer faces of said plates and a relatively narrow web portion of substantially the same magnetic cross section as each perforate flange across approximately the lower half of the gap between the plates at the rear edge thereof and provided with a non-magnetic mounting member interconnecting said flanges behind said barrier, a stud terminal head engaging said plates behind said barrier for clamping said non-magnetic member in mounting position, a contact, means resiliently mounting said contact between said plates in front of and adjacent the web portion of said U-shaped member, an electric current conductor looped around said web portion from the rear to the front thereof and connected between said relatively stationary contact and said terminal head, and a cooperating contact mounted for movement between said plates near the lower edge thereof to engage said relatively stationary contact and separable therefrom to interrupt a circuit within the chute.

2. In an electric switch, an arc chute open at the top, front and bottom edges comprising two oppositely spaced rectangular plates of electrically insulating material having an insulating barrier closing the upper part of the gap between the rear edges thereof, a U-shaped magnetic member having upwardly offset flange portions embracing said plates and a relatively narrow web portion partially closing the lower part of the gap between the rear edges of said plates, a terminal stud having a mounting head engaging the plates behind said insulating barrier, a relatively stationary switch contact resiliently suspended from said head between said plates in front of and adjacent the web portion of said U-shaped member, a flexible electric current conductor extending from said terminal mounting head in a magnetizing loop around said web portion from the rear to the front thereof, said conductor being connected to said relatively stationary switch contact and terminating thereat, and a cooperating movable switch contact mounted for movement between said plates near the lower edge thereof to engage said relatively stationary switch contact and separably therefrom to interrupt a circuit within the chute.

3. In an electric switch, an arc chute open at the top, front and bottom edges thereof comprising oppositely spaced rectangular plates of an electrically insulating material having the upper half of the inner walls thereof converging to form an upward discharge channel, an insulating spacer barrier mounted between said plates to close the gap between the rear edges of said converging walls, a U-shaped magnetic member having upwardly offset perforate flange portions embracing said plates and a relatively narrow web portion of substantially the same magnetic cross section as each perforate flange partially closing the lower half of the gap between the plates at the rear edge thereof, a terminal stud having a mounting head engaging the plates behind the spacer barrier, a relatively stationary switch contact suspended from said head between said plates in front of and adjacent the web portion of said U-shaped member, and an electric current conductor extending from said terminal head in a magnetized loop around said web portion from the rear to the front thereof, said conductor being connected to said relatively

7
stationary contact and terminated thereat, and a cooperating contact mounted for movement between said plates near the lower edge thereof to engage said relatively stationary contact and separably therefrom to interrupt a circuit within the chute.
